(57) **CLAIM**

I claim the ornamental design for a Keymod forearm for an AR-15 rifle, as shown and described.

DESCRIPTION

FIG. 1 is a top perspective view of a Keymod forearm for an AR-15 rifle, showing my new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof;

FIG. 5 is a bottom plan view thereof; and,

FIG. 6 is an enlarged bottom perspective view thereof.

1 Claim, 4 Drawing Sheets
